UNITED STATES PATENT OFFICE

154,728

DESIGN FOR AN ELECTRODE HOLDER

Charles K. Wilson, East Williston, and Joshua G.
Lippincott, Scarsdale, N. Y.

Application December 9, 1948, Serial No. 150,059

Term of patent 14 years

(Cl. D26—1)

To all whom it may concern:

Be it known that we, Charles K. Wilson and Joshua G. Lippincott, citizens of the United States, respectively residing at East Williston, L. I., New York, and Scarsdale, New York, have invented a new, original, and ornamental Design for an Electrode Holder, of which the following is a specification, reference being had to the accompanying drawings, forming part thereof, in which

Fig. 1 is a side elevational view of an electrode holder, showing our new design;

Fig. 2 is a perspective view of the electrode holder shown in Fig. 1.

The opposite side of the device is substantially the same as that shown in Fig. 1.

We claim:

The ornamental design for an electrode holder, as shown and described.

CHARLES K. WILSON.
JOSHUA G. LIPPINCOTT.
